(57) **CLAIM**

I claim the ornamental design for a casing for data processing equipment, as shown.

DESCRIPTION

FIG. 1 is a black-and-white line drawing evidencing a left view thereof.

FIG. 2 is a black-and-white line drawing evidencing a top view thereof.

FIG. 3 is a black-and-white line drawing evidencing a perspective view thereof.

FIG. 4 is a black-and-white line drawing evidencing a right side view thereof.

FIG. 5 is a black-and-white line drawing evidencing a rear view thereof.

FIG. 6 is a black-and-white line drawing evidencing a bottom view thereof; and,

FIG. 7 is a black-and-white line drawing evidencing a front view thereof.
